PNEUMATIC THREAD HOLDER FOR WEFT REPLENISHING LOOMS

Gabriel C. Beatrice, Shrewsbury, Mass., assignor to Crompton & Knowles Loom Works, Worcester, Mass., a corporation of Massachusetts

Application November 2, 1950, Serial No. 193,675

11 Claims. (Cl. 139—247)

1 This invention relates to improvements in pneumatic thread holders for weft replenishing looms and it is the general object of the invention to provide simple means for separating the several weft ends leading from reserve bobbins of the magazine to the interior of the thread holder.

Weft replenishing looms more particularly of the multicolor type employ a magazine provided with stacks of reserve bobbins from which weft ends lead to a form of thread holder. When a thread holder of the pneumatic type is used the threads extend through an intake mouth and into an interior thread chamber where they are subjected to subatmospheric pressures. The bobbins which are stored in the magazine for future replenishing operations may remain in the magazine for several hours before being used and during this time the weft ends have an opportunity to become wrapped on each other or become otherwise entangled so that they cannot be properly drawn into the thread holder when a weft replenishing operation occurs.

It is an important object of the present invention to provide a pneumatic thread holder constructed with spacing elements or the like within the thread compartment close to the thread intake mouth and so located as to separate the threads or weft ends to prevent them from becoming entangled or wrapped on each other.

In a known form of pneumatic thread holder such for instance as shown in prior patents to Turner No. 2,476,640 and 2,505,443 the thread compartment has the upper end thereof closed by a cover which is raised when new bobbins are inserted in the magazine to receive the fresh weft ends. In such a thread holder the weft ends extend across the upper part of the thread compartment and hang from an outer side of a thread holder to be drawn into the compartment when the cover is closed. It is another object of the present invention to locate the aforesaid spacing elements so that they will extend above the path normally traversed by the weft ends across the upper part of the thread compartment, thereby insuring entry of the weft ends into the spaces between the elements when the cover returns to its normal down position.

The latter of the previously mentioned patents shows a series of prongs which extend downwardly from the thread holder into a thread collector for the purpose of preventing weft ends from being drawn out of the holder on the first pick subsequent to replenishing operations. It is a further object of the present invention to provide a simple form of unit combining the previously mentioned

spacing elements and the prongs, the unit being readily attachable to the thread holder. In order that the weft ends may be drawn efficiently into the thread holder the unit is so made that a column of air entering the thread intake mouth and moving toward the thread collector can pass around all sides of the weft ends.

With these and other objects in view which will appear as the description proceeds, the invention resides in the combination and arrangement of parts hereinafter described and set forth.

In the accompanying drawings, wherein two forms of the invention are set forth,

Fig. 1 is a side elevational of part of a weft replenishing loom having the preferred form of the invention applied thereto,

Fig. 2 is an enlarged plan view looking in the direction of arrow 2, Fig. 1,

Fig. 3 is an enlarged detail vertical section on line 3—3, Fig. 2,

Fig. 4 is a detail plan view looking in the direction of arrow 4, Fig. 3,

Fig. 5 is a fragmentary vertical section on line 5—5, Fig. 3,

Fig. 6 is a perspective view of the preferred form of unit, and

Fig. 7 is a view similar to a portion of Fig. 3, but showing the modified form of unit.

Referring particularly to Fig. 1, the loom frame 30 supports a top shaft 2 which by connectors one of which is shown at 3 reciprocates a lay 4 backwardly and forwardly. The loom is provided with a magazine M which in the present instance is of the stationary multicolor type and has a group 35 of weft ends W extending from reserve bobbins B to a thread holder designated generally at H. The holder is mounted on a hollow thread collector C which in turn is supported by an upright 5.

An air pump 6 secured to the loom frame is operated by a lever 7 connected by rod 8 to the lay 4. A hose or other flexible hollow connector 9 leads from the pump forwardly to the lower end of the collector C and communicates with the interior of the latter to create subatmospheric pressures therein.

The thread holder as shown more particularly in Figs. 2 and 3 comprises a hollow walled structure including a base 10 formed with an upright inner wall 11, at the left in Fig. 3, an outer wall 12, and connecting front and back walls 13 and 14, respectively. These walls form or enclose a thread compartment 15 the upper part of which is normally closed by a cover 16 pivoted to the holder as at 17. The upper part of wall 11 is formed with a recess 18 which together with the

adjacent part of the cover 16 forms an elongated horizontal thread intake mouth 19 into which the weft ends W extend. The mouth communicates pneumatically with the interior of the compartment 15 and a column of air moving into the mouth and through the compartment will be drawn downwardly through an opening 20 in the base or floor 10 communicating with the interior of the thread collector C. The upper part of the outer wall 12 is recessed as at 22 to form a second mouth 23 with the cover.

When the loom is in operation the pump 6 will create subatmospheric pressures within the collector C and compartment 15 and draw air into the mouth 19 to create tension in the weft threads W. When new bobbins are placed in the magazine their weft ends are slipped under the end 24 of cover 16 to lift the latter and are then moved rearwardly and drawn across the top of the compartment 15 through the recess 22 and released to hang down from the right end of the holder as viewed in Fig. 3. When the cover returns to normal position subatmospheric pressures within the compartment 15 will draw the free ends of the weft threads through the mouth 23 into the thread compartment and down through the opening 20 into the collector C. A set of prongs 25 to be described in more detail hereinafter is located at one side of the opening 20, namely the side thereof adjacent the intake mouth 19, and the weft ends will lie along these prongs and eventually become sufficiently entangled with each other within the collector so that the prongs will prevent the threads from retrograde movement out of the mouth 19. When a weft end is cut at the selvage it will be drawn into the holder and traverse a path from mouth 19 through opening 20 into the collector.

The matter thus far described may be as set forth in the previously mentioned patents and except as noted hereinafter forms no part of the present invention.

In carrying the present invention into effect there is provided a series or row of thread spacing fingers or elements 30 which are located within the thread compartment 15 but closely adjacent to the mouth 19. These finger elements, which may be made of smooth round wire, extend in a series preferably parallel to the mouth 19 and are inclined upwardly and away from the mouth as shown for instance in Fig. 3. The under surface 31 of the cover is provided with a downwardly opening groove or slot 32 extending upwardly from the surface 31 and into which the upper ends of the finger or spacing elements extend to points above the under side of the cover. When the latter is in the normal down position shown in Fig. 3, therefore, weft threads extending from the intake mouth 19 to the opposite mouth 23 will be below the tops of the fingers or spacers 30.

The spacers 30 may be supported by the preferred form of unit shown in Fig. 6 or by the modified form of unit shown in Fig. 7. The preferred form of unit 35 may be made of sheet metal and has a flange 36 to which the spacer elements 30 are secured. The flange is integral with a hollow plate 37 which leads to the right and downwardly as viewed in Fig. 3 and is formed at its sides with ears 38 by which the unit is secured to the bottom of base 10 by screws 39. A second flange 40 depending from plate 37 has the previously described prongs 25 secured thereto. The plate 37 is formed with a

relatively large opening 41 across which the weft ends extend from the spacing elements 30 to the prongs 25 so that a column of air passing from the intake mouth 19 to the opening 20 will have an opportunity to act on all sides of the weft ends. The screws 39 hold the unit 35 with the left edge 42 of flange 36 against the inner surface 43 of wall 11, thus holding the elements 30 fixed with respect to the holder.

In the modified form of the invention shown in Fig. 7 the unit 45 may be formed substantially as the unit 35 except that instead of the opening 41 the plate 46 corresponding to plate 37 is made concave as at 47 to enable air to get under the threads leading from the intake mouth to the opening 20.

In the operation of the invention weft ends from the bobbins B extend through the intake mouth 19 and between the several spacers 30 and are held separated by the latter so that they will not become entangled or twisted with each other. Upon occurrence of a weft replenishing operation the corresponding weft end will therefore be able to move freely into the thread compartment 15 without interference by neighboring threads. In order to enable the thread thus drawn into the holder to clear itself of the adjacent spacing elements the latter should preferably be inclined sufficiently in a direction away from the mouth 19 to enable the thread to slip over the ends of the elements. This result can be accomplished by having the elements 30 inclined away from mouth 19 and toward the direction in which the threads move toward opening 20. Since the flanges 36 and 40 will ordinarily determine the direction of the weft threads as they extend through the thread compartment 15 the thread spacer elements 30 can be secured to the unit 35 so as to be inclined in a direction from flange 36 toward flange 40. This relationship is also desirable for the modified form of the invention shown in Fig. 7 in which the unit 45 has a left hand flange 48 corresponding to flange 36 and a right hand flange 49 as viewed in Fig. 7 corresponding to flange 40. The ears 38 preferably are secured to the base 10 in such manner as not to reduce the width of the opening 20 as will be understood more particularly from Fig. 4, and the prongs 25 extend downwardly from a space between the ears in each form of the invention.

From the foregoing it will be understood that the invention sets forth simple means for separating the weft ends leading from the reserve bobbins B into the thread compartment 15, this means comprising a plurality of spacing fingers or elements which extend in a line close to and preferably parallel to the mouth 19 but within compartment 15. The spacing elements are preferably inclined in a direction away from the direction of entry of air passing from the mouth 19 to the opening 20 so that the weft ends of transferred bobbins may clear themselves of adjacent elements 30 when drawn into the compartment 15 subsequent to cutting after the replenishing operation. The elements 30 preferably extend upwardly so that their top ends are above any position which weft ends can occupy in the compartment 15 when the cover is in its normal position. As shown herein the cover is provided with a groove 32 to receive the upper ends of the elements 30, but it is to be understood that this is not the only way in which the spacing elements can project above the weft threads extending from the intake mouth 19 along the under side

of the cover to the opposite mouth 23. Furthermore, the invention sets forth a simple form of unit having a set of spacer elements for the intake mouth and a series of prongs 25 for the opening 20. The element is so made that air passing from the intake mouth to the opening 20 can act on all sides of the weft ends within the compartment 15. The unit is preferably formed with ears for attachment to the base 10 which locate the left edge of the flanges 36 and 45 as shown in Figs. 6 and 7, respectively, close to or in engagement with the wall 11 and below the mouth 19 to prevent threads from being drawn into the space under the unit.

Having thus described the invention it will be seen that changes and modifications of the foregoing specific disclosure may be made without departing from the spirit and scope of the invention.

What is claimed as new is:

1. In a pneumatic thread holder for the weft ends of reserve bobbins in a loom, a walled structure enclosing a thread compartment in which subatmospheric pressures exist, the holder having a mouth communicating with the compartment and through which the weft ends extend into the compartment, a cover for the top of said walled structure movable upwardly to permit insertion of weft ends into the compartment, and a series of thread spacers fixed with respect to the structure within said compartment adjacent to said mouth and below the cover to separate the weft ends from each other, said spacers extending upwardly above weft ends extending along the under side of the cover.

2. In a pneumatic thread holder for the weft ends of reserve bobbins in a loom, a walled structure having a recess in the upper part of one of the walls thereof, a cover for the top of the structure forming with said recess a mouth through which the weft ends extend, said walled structure and cover enclosing a thread compartment in which subatmospheric pressures exist and into which the weft ends extend, and a series of thread spacing fingers fixed with respect to the structure adjacent to said mouth below said cover, the under side of said cover having a slot therein into which the upper ends of said spacer fingers extend, said spacing fingers separating the weft ends from each other.

3. In a pneumatic thread holder for the weft ends of reserve bobbins in a loom, a hollow structure having a base provided with an opening, a hollow thread collector below the base communicating through said opening with the interior of the hollow structure, means creating subatmospheric pressures within the hollow structure and thread collector, the hollow structure having a thread intake mouth, the weft ends extending through said mouth into said structure and through the opening into the collector, and a series of thread spacers within the hollow structure adjacent the intake mouth extending across the path traversed by the weft ends as the latter extend from the intake mouth to said opening, said thread spacers separating the weft ends from each other.

4. In a combined pneumatic thread holder and

thread collector for the weft ends of reserve bobbins in a loom, a hollow thread holder having an intake mouth for the weft ends and enclosing a thread compartment, a thread collector in pneumatic communication with said compartment and mouth and within which subatmospheric pressures exist, and a unit within said holder provided with a series of thread spacing elements adjacent to said intake mouth and separating the weft ends, the latter extending into said mouth between said elements and through the thread holder into the thread collector.

5. The structure set forth in claim 4 wherein said unit is provided with a series of prongs projecting into the thread collector.

6. The structure set forth in claim 4 wherein said unit comprises a plate across which the weft ends extend from said spacing elements into said collector, said plate affording access of air moving from the mouth to the collector to all sides of the weft ends.

7. The structure set forth in claim 4 wherein said unit has a flange engaging the interior of the holder adjacent to said intake mouth and on which said thread spacing elements are mounted.

8. The structure set forth in claim 4 wherein said unit is formed with a flange extending along the intake mouth and supporting said thread spacing fingers and is provided with a second flange on which are mounted prongs extending into the thread collector.

9. A thread spacing unit for a pneumatic thread holder having a hollow thread compartment communicating with a thread intake mouth and within which subatmospheric pressures exist, said unit comprising a plate formed for attachment to the holder within said compartment, a flange formed as part of the plate to be adjacent to said mouth when the unit is attached to the holder within the compartment, a second flange formed as part of the plate spaced from the first flange, a series of thread spacing elements fixed to the first flange, and a series of prongs fixed to the second flange and extending from the latter in a direction away from said series of spacing elements.

10. The thread spacing unit set forth in claim 9 wherein the plate has ears extending from said second flange for attachment to said thread holder.

11. The thread spacing unit set forth in claim 9 wherein said plate is formed so as to afford access of air to all sides of a thread drawn taut from the first flange to the second flange.
